CLAIM

I claim the ornamental design for a dominoes tile set, as shown and described.

DESCRIPTION

FIG. 1 is a top, front perspective view of a domino tile of the dominoes tile set;

FIG. 2 is a bottom, front perspective view thereof;

FIG. 3 is a top plan view thereof;

FIG. 4 is a bottom plan view thereof;

FIG. 5 is a left-side view thereof;

FIG. 6 is a right-side view thereof;

FIG. 7 is a rear elevation view thereof;

FIG. 8 is a front elevation view thereof; and,

FIG. 9 is a bottom plan view of the domino tile set. each domino tile is identical to the dominoes tile set illustrated in FIGS. 1-8, except for the dots pattern located on the bottom surface of each of the domino tile.

The pattern shown on the surfaces of the dominoes tile set represents a wood grain appearance that is continuous throughout the surfaces on which it is shown.

The broken lines in the figures illustrate portions of the dominoes tile set that form no part of the claimed design.
